(57) **CLAIM**

The ornamental design for a cap, as shown and described.

DESCRIPTION

FIG. 1 is a first top perspective view of a first embodiment of a cap, showing my new design.

FIG. 2 is a top plan view of the cap of FIG. 1.

FIG. 3 is a bottom plan view of the cap of FIG. 1.

FIG. 4 is a first side elevation view of the cap of FIG. 1.

FIG. 5 is a second side elevation view of the cap of FIG. 1.

FIG. 6 is a third side elevation view of the cap of FIG. 1.

FIG. 7 is a bottom perspective view of the cap of FIG. 1.

FIG. 8 is an exploded top perspective view of the cap of FIG. 1, shown in a position of use with an exemplary bottle.

FIG. 9 is a top perspective view of the cap of FIG. 8, shown with the cap positioned on the exemplary bottle.

FIG. 10 is a top perspective view of a second embodiment of a cap, showing my new design.

FIG. 11 is a top plan view of the cap of FIG. 10.

FIG. 12 is a bottom plan view of the cap of FIG. 10.

FIG. 13 is a first side elevation view of the cap of FIG. 10.

FIG. 14 is a second side elevation view of the cap of FIG. 10.

FIG. 15 is a third side elevation view of the cap of FIG. 10.

FIG. 16 is a bottom perspective view of the cap of FIG. 10.

FIG. 17 is an exploded top perspective view of the cap of FIG. 10, shown in a position of use with an exemplary bottle.

FIG. 18 is a top perspective view of the cap of FIG. 17, shown with the cap positioned on the exemplary bottle.

FIG. 19 is a top perspective view of a third embodiment of a cap, showing my new design.

FIG. 20 is a top plan view of the cap of FIG. 19.

FIG. 21 is a bottom plan view of the cap of FIG. 19.

FIG. 22 is a first side elevation view of the cap of FIG. 19.

FIG. 23

is a second side elevation view of the cap of FIG. 19.

FIG. 24 is a third side elevation view of the cap of FIG. 19.

FIG. 25 is a bottom perspective view of the cap of FIG. 19.

FIG. 26 is an exploded top perspective view of the cap of FIG. 19, shown in a position of use with an exemplary bottle; and,

FIG. 27 is a top perspective view of the cap of FIG. 26, shown with the cap positioned on exemplary bottle.

The broken lines are shown for the purpose of illustrating both parts of the article as well as environmental subject matter of an exemplary bottle. None of the broken lines form part of the claim.

1 Claim, 12 Drawing Sheets
